UNITED STATES PATENT OFFICE.

ALBERT LONG AND ROBERT FOSTER, OF LAWRENCE, MASSACHUSETTS.

APPARATUS FOR DRAWING OFF IN CIRCLE-COMBS.

SPECIFICATION forming part of Letters Patent No. 606,564, dated June 28, 1898.

Application filed October 8, 1897. Serial No. 654,497. (No model.)

To all whom it may concern:

Be it known that we, ALBERT LONG and ROBERT FOSTER, of Lawrence, in the county of Essex and State of Massachusetts, have 5 invented certain new and useful Improvements in Apparatus for Drawing Off in Circle-Combs, of which the following is a specification.

This invention relates to circle-combs, and 10 is hereinafter described in connection with a wool-comb of the type known as the "Noble" comb.

The invention has for its object to provide 15 an improved method of and means for drawing off the wool and for conducting the same from one set of drawing-off rolls to the other set. Heretofore the drawing off has been 20 accomplished by means of fluted rolls and leather aprons so arranged as to take the projecting fibers of wool from the combs and 25 form the same into a sliver, that portion which is drawn from the large comb or circle being conducted between the leather aprons from the drawing-off rolls of the large circle 30 to the drawing-off rolls of the small circle, where it combines with the wool from the small circle to form the sliver. This method is open to several objections well known to 35 those skilled in the art of combing wool, the two principal ones being the wear on the leather aprons and the frequent breaking of the sliver, caused by the wool from the large circle following the aprons around instead of 40 passing between the drawing-off rolls of the small circle. The wear on the aprons is very considerable and requires them to be frequently renewed, thus involving expense and trouble. The breaking of the sliver is disadvantageous in itself and also because it requires the stoppage of the comb and consequent loss of time.

By means of the present invention the leather aprons are dispensed with and the drawing off accomplished by smooth-surfaced rolls, an improved conducting device 45 being also provided for conducting the wool from one drawing-off head to the other.

The invention consists in the novel features of construction and arrangement which will 50 now be explained with the aid of the accom-

panying drawings, forming a part of this application, and then pointed out in the claims hereto annexed.

Of the drawings, Figure 1 represents a top plan view of the improved drawing-off heads 55 and the sliver-conducting devices interposed therebetween. Fig. 2 represents a side elevation of the same with portions of the machine broken away, looking in the direction of the arrow 1, Fig. 1. Fig. 3 represents a 60 side elevation looking in the opposite direction. Fig. 4 represents a horizontal section on the line 4 4 of Fig. 2. Fig. 5 represents a vertical longitudinal section of the upper portion of the machine on the line 5 5 of Fig. 1. 65 Fig. 6 represents an enlarged side elevation of one of the drawing-off heads. Fig. 7 represents a section on the line 7 7 of Fig. 6. Fig. 8 represents a section on the line 8 8 of Fig. 6. Fig. 9 represents a section on the line 9 9 of Fig. 6. Fig. 10 represents a dia- 70 grammatic plan of the machine with the parts in operative positions. Fig. 11 represents a section on the line 11 11 of Fig. 2.

The same reference characters indicate the 75 same parts in all the figures.

Referring to the drawings, l^5 in Fig. 10 designates the large circle of a Noble comb, and l^4 one of the small circles. For the purpose of drawing the wool from the teeth of 80 the large circle we provide, in place of the usual two fluted rolls and leather apron, four smooth-surfaced rolls k^3 k^4 k^5 k^6 , arranged in a train and bearing against each other at three points, so as to have three "nips" on 85 the sliver. For certain kinds of wool and in certain cases it may suffice to have only three rolls in this head, but for general work we prefer to have four, as shown. The fibers of wool are drawn, as shown in Fig. 10, from 90 between the teeth on the large circle, and passing in the form of a sliver between the rolls of the drawing-head they are conducted, by means of a conducting device hereinafter described, to the other drawing-head adjacent to the small circle. Here they meet and blend with the fibers of wool from said small circle, passing between the rolls therewith and uniting to form a single sliver in the ordinary manner. There are three rolls 95 100

in this head, smooth-surfaced like those in the other drawing-head. The mounting of the rolls in each head is as follows:

25 *a a* designate supporting-standards mounted on a base *b* and broadened at their upper ends to form tables *c c*, on which rest the two drawing-heads *d* and *e*, which pivotally surround driving-shafts *f* and *a³*. The group of rolls corresponding to the small circle *l¹* of the comb comprises a roll *g*, formed as an enlargement on the upper end of the shaft *f*, and two other rolls *r* and *s*. The roll-shafts are provided with gears *o p q*, whereby the rolls *r* and *s* are driven by the roll *g*. The 15 shaft *f* is supported in suitable bearings *h i* on the frame *a* and is provided below the base *b* with a gear *j*, adapted to mesh with a suitable driving-gear. (Not shown.) Rotatory motion is transmitted from the shaft *f* 20 to the shaft *a³* by suitable intermeshing gears *a⁴ a⁵ a⁶*, receiving motion from the gear *j*. In the drawing-head *e* the roll *k⁶* is the driver and the other three are driven by gears from this roll in the same manner as the rolls in 25 the head *d*.

In order that the tension of the rolls in each head upon the sliver may be adjusted, yielding bearings are provided for the rolls *r s* and for the rolls *k³ k⁴ k⁵*. These bearings are 30 best illustrated in Figs. 6 to 9, which show the construction of the drawing-head *d*. Recesses *t u* are formed in the frame of the head *d*, and in said recesses are mounted carriers *v w*, which are retained in position by overlapping edge plates *a' a' k*, bolted to the head, and by the upper and lower walls of the recesses in which the carriers are mounted. To said carriers are bolted brackets *b' c'*, having sleeves *b² c²* at their outer ends, which 35 support and journal the rolls *r s*. The carriers *v w* are provided with enlarged portions *l*, forming sockets *k'*, in which are located spiral springs *j'*. Said springs press against the ends of the sockets and against plunger-blocks *i'*, which are backed by adjusting-screws *g'*. In this way the rolls *r s* are yieldingly actuated toward the roll *g*, and the amount of pressure upon the wool sliver is 40 regulated with the adjusting-screws *g'*. The 45 mounting of the rolls *k³ k⁴ k⁵* in the other drawing-head is similar to that of the rolls *r s*, with the addition of a third yieldingly-mounted roll.

The heads are adapted to be moved radially 55 upon their respective shafts a limited distance in order to adjust the outer surfaces of the rolls to the circular combs. They are secured in position by bolts *c³*, Figs. 6 and 7, passing through circular slots in the tables *c* 60 and screwing into the heads. The shafts *f* and *a³* turn in bushings *b⁴*, Fig. 5, which pass loosely through sleeves *b³*, formed on each head, and are secured by means of set-screws *b⁶* in journals on the standards *a*. 65 In order that the drawing-rolls of each head may be adjusted toward and away from their

respective circles for the purpose of regulating the closeness of the nip, the standards *a* are provided with slots *a⁷ a⁸*, through which pass the bolts *a⁹ a⁸*, which clamp said standards to the base *b*. When, therefore, it is desired to move the drawing-heads bodily, the nuts on said bolts are loosened and the standards, together with their shafts, are moved a small distance, though not sufficiently to disengage the gears underneath the base *b*, the bolts being then tightened up again. 75

It is to be noted with respect to those drawing-rolls in each head which are mounted in yielding bearings that both ends of each roll 80 are journaled in a single carrier, so that the roll is moved bodily instead of having its ends independently adjustable, which is the practice with the fluted rolls employed on machines now in use. The improved construction here shown gives an even contact 85 throughout the length of each roll and permits of a single adjustment for both bearings of the roll instead of two adjustments, as formerly.

The mounting of both bearings of the roll in a solid frame or carrier is an important feature, since it is essential to the best results that the surfaces of the rolls be, as nearly as possible, exactly parallel at all times. It will 95 further be noted that the bearings of each roll are placed as near together as possible, and the roll is of very stout construction in order to prevent any possibility of buckling. 90

The particular arrangement of drawing-off 100 rolls which we have invented produces what may be termed a "lock-nip" on the wool. This lock-nip consists in the action produced by two smooth-faced positively-driven rolls co-operating at separate points with a third positively-driven smooth-faced roll. In the case 105 of the drawing-head *c* of the large circle the wool is engaged with a double lock-nip—that is, there is the lock-nip produced by the three rolls *k³ k⁴ k⁵* and that produced by the three 110 rolls *k⁴ k⁵ k⁶*. The powerful drawing action which results is adequate to draw the wool from between the teeth of the large circle, and is, we have found, even superior to that produced by fluted rolls and leathers. In the 115 case of the small circle, which holds its wool less tenaciously, three drawing-rolls are sufficient, though we have found that this is the least number which can be depended upon to do satisfactory work under all conditions. 120

d³ designates a supporting-frame intermediate of the drawing-heads, the said frame resting on extended portions *d⁴ d⁵* of the said heads and being movably secured thereto by shouldered bolts *j⁵ j⁶* passing through slots *j³ j⁴* in said frame. This arrangement allows the drawing-heads to be moved independently of the frame *d³*. Standards *d⁶ d⁷* on the frame support a pair of horizontal rolls *d⁸ d⁹*, the upper roll *d⁸* being yieldingly arranged upon 125 the lower one *d⁹* and pressed downwardly thereon by means of springs *d¹⁰* in the tops of 130

the standards. (See Fig. 3.) On the shafts of the two rolls are intermeshing gears e^3 e^4 , and on the shaft of the lower one is a bevel-gear e^5 , which meshes with a bevel-gear e^6 , secured to a vertical shaft e^7 . Said shaft is journaled in a sleeve e^8 , secured to the supporting-frame d^3 , and is rotated by means of a sprocket-chain f^4 , engaging sprocket-wheels f^3 and f^5 on the shafts e^7 and f , respectively.

10 The chain is normally held taut by means of a spring j^7 , attached to the head e and to a stud m' , projecting from the under side of the frame d^3 . On said stud is mounted a roller m , which bears against the edge of a cam-plate n on the under side of the head d and co-operates therewith in resisting the pull of the chain. The various positions of the drawing-head d with respect to the frame d^3 require the cam-plate n to be adjustable in order to maintain the chain f^4 at its proper degree of tautness, and for this purpose said plate is provided, Fig. 11, with a pivot-pin n' , extending up into the bed-plate of the head d , and with clamping-screws n^2 n^3 , extending through circular slots in the cam-plate. When the cam-plate is to be adjusted, the screws n^2 n^3 are loosened, the plate turned on its pivot to the required adjustment, and the screws then tightened to clamp the plate in place.

30 Guiding troughs or conduits g^4 g^4 for the support of the sliver as it approaches and leaves the rolls d^8 d^9 are adjustably mounted between ears g^3 g^3 , formed on the frame d^3 . The trunnions of said conduits are closely fitted in their bearings, so that when tilted to a certain position the conduits will remain in that position. The trunnions are provided outside the ears g^3 with handles g^5 g^5 , whereby the conduits may be tilted. These guiding troughs or conduits are supplemented by pivoted funnels or bell-shaped conductors i^2 i^3 , whose shanks i^4 i^5 are loosely held in sleeves i^6 i^7 , formed upon the heels of the guiding conduits.

45 The operation of the machine as applied to a Noble comb is best illustrated in Fig. 10. The long wool from the teeth of the large circle or comb b^5 is drawn off between the rolls k^3 k^4 k^5 k^6 , passing through the bell-guide adjacent thereto and along the guiding-trough through the horizontal rolls d^8 d^9 and through the other trough and bell-guide to the drawing-rolls r s t . Here it meets the short wool from the smaller comb b^4 , and the two are blended into one sliver in passing between the latter rolls. This sliver is passed forward into a can for future operations.

Having thus explained the nature of the invention and described a way of constructing and using the same, though without attempting to set forth all of the forms in which it may be made or all of the modes of its use, we declare that what we claim is—

1. In a circle-comb, the combination with the toothed circles and means for operating them, of a set of three or more smooth-surfaced drawing-off rolls adapted to engage the

wool between their adjacent surfaces, and means for positively and continuously driving said rolls.

2. In a circle-comb, a drawing-off device comprising a smooth-surfaced roll, two other smooth-surfaced rolls coacting with the first roll at separate points to engage the wool, and means for positively and continuously driving said rolls.

3. In a circle-comb, a drawing-off device comprising a driving-shaft carrying a smooth-surfaced roll and a gear, means for continuously rotating said shaft, and two other smooth-surfaced rolls provided with gears on their shafts meshing with the gear on the driving-shaft, the rolls being adapted to engage the wool between their adjacent surfaces.

4. In a circle-comb, the combination with the large and small toothed circles and means for operating them, of a series of smooth-surfaced drawing-off rolls adjacent to the large circle and adapted to engage and draw off the wool therefrom between their adjacent surfaces, means for positively and continuously driving said rolls, a series of smooth-surfaced drawing-off rolls adjacent to the small circle and adapted to engage and draw off the wool therefrom between their adjacent surfaces and to combine it with a sliver from the large circle to form a single sliver, means for positively and continuously driving said rolls, and means for guiding the sliver from the drawing-off rolls of the large circle to those of the small circle.

5. In a circle-comb, the combination with the toothed circles and means for operating them, of drawing-off devices adjacent to the respective circles, means for operating said devices, and intermediate means for guiding and advancing a sliver from one set of drawing-off devices to the other, the said means comprising a set of coacting smooth-surfaced rolls adapted to engage the wool between their adjacent surfaces, and means for positively driving said rolls.

6. In a circle-comb, drawing-off devices adjacent to the large and small toothed circles, coacting rolls adapted to guide and advance a sliver from the drawing-off devices of one circle to those of the other, and stationary devices for supporting and guiding the sliver between said rolls and the drawing-off devices.

7. In a circular wool-combing machine, the combination with the large and small circles of drawing-off devices adjacent to each circle, and means for conducting a sliver from the drawing-off devices of the large circle to those of the small circle, the said means comprising a set of coacting smooth-surfaced rolls, guiding troughs or conduits on either side of said rolls, and funnel-shaped guides at opposite ends of said troughs.

8. In a drawing-off device for a circle-comb, the combination of a drawing-roll and bearings therefor, a frame, a carrier provided with

bearings fixed thereto, a roll journaled in said bearings, a connection between the frame and carrier to permit the latter to slide but prevent tilting thereof in the former, and means for sliding the carrier in the frame, whereby the parallel relation of the rolls is not changed as they are moved toward or away from each other.

9. In a circular wool-combing machine, two drawing-heads having smooth-surfaced drawing-off rolls, and an intermediate guiding mechanism comprising a frame adjustably mounted between and carried by said drawing-heads and suitable guiding devices on said frame adapted to guide a sliver from the rolls of one drawing-head to the rolls of the other.

10. In a circle-comb, a drawing-off device comprising a driving-shaft provided with a gear and carrying a smooth-surfaced drawing-roll, a frame or head pivotally embracing said shaft, solid frames or carriers mounted to slide in guides on said head, smooth-surfaced drawing-rolls supported in bearings on said frames and having gears mounted on their shafts and meshing with the gear on the driving-shaft, and springs interposed between the sliding carriers and the heads and operating to yieldingly actuate the carriers and their rolls toward the roll on the driving-shaft.

11. In a circle-comb, two drawing-heads provided with drawing-rolls and shafts for driving said rolls, intermediate rolls supported between said heads for guiding and advancing a sliver from one head to the other, and a sprocket-and-chain device connected with one of the driving-shafts and with said intermediate rolls, for driving the latter.

12. In a circular wool-combing machine, in combination, two independent linearly and pivotally adjustable drawing-heads having drawing-off rolls, vertical shafts for driving said rolls, an intermediate frame adjustably supported on said drawing-heads, conducting-rolls mounted on said frame for conducting a sliver from one drawing-head to the other, a sprocket-and-chain device for driving said conducting-rolls from one of the vertical shafts, a roller carried by the frame and an adjustable cam-plate coöperating with said roller to adjust said sprocket-and-chain device.

13. In a drawing-off device for a circle-comb, the combination of a drawing-roll, and bearings therefor, a frame, a carrier provided with bearings fixed thereto, a roll journaled in said bearings, a connection between the frame and carrier to permit the carrier to slide but prevent tilting thereof in the frame, and a yielding adjusting means for sliding the carrier in the frame.

14. In a drawing-off device for a circle-

comb, the combination of a drawing-roll and bearings therefor, a frame, a carrier provided with bearings fixed thereto and mounted in said frame, a roll journaled in the said bearings on the carrier, a guiding connection between the frame and carrier to permit the latter to slide but prevent tilting thereof in the former, and a single set-screw for sliding the carrier in the frame.

15. The combination of the drawing-heads and drawing-off rolls, of a frame supported between said heads, conducting-rolls mounted on said frame, and means for driving the conducting-rolls from the drawing-rolls.

16. In a circle-comb, the combination of the drawing-heads and drawing-rolls, of a frame adjustably mounted between said heads, conducting-rolls mounted on said frame, and means for driving the conducting-rolls from the drawing-rolls including a sprocket-and-chain connection and means for adjusting the frame between the drawing-heads.

17. In a circle-comb, the combination of the drawing-heads and sets of drawing-rolls, of a frame, supports between said heads, conducting-rolls carried by said frame, and means including a sprocket-and-chain connection for driving the conducting-rolls from the drawing-rolls, a roller on the frame and a cam-plate adjustably mounted on one of the drawing-heads whereby to adjust the frame toward and away from one set of drawing-rolls and thereby adjust the sprocket-and-chain connection.

18. In a circle-comb, the combination of the drawing-heads and sets of drawing-rolls, of a stationary guide for supporting the sliver between the sets of drawing-rolls.

19. In a circle-comb, the combination of the drawing-heads and sets of rolls, of a stationary guide for supporting the sliver between the sets of drawing-rolls, and means at the end of the stationary guide for leading the sliver from the drawing-rolls to said guide.

20. In a circle-comb, the combination of the drawing-heads and sets of drawing-rolls, of a stationary guide for supporting the sliver between the sets of drawing-rolls, and trumpets pivotally mounted at the ends of the guide for leading the sliver from the first set of drawing-rolls to the guide and from the guide to the second set of drawing-rolls.

In testimony whereof we have signed our names to this specification, in the presence of two subscribing witnesses, this 30th day of September, A. D. 1897.

ALBERT LONG.
ROBERT FOSTER.
